UNITED STATES PATENT OFFICE.

ROBERT B. COCHRANE, OF CHARLOTTE, NORTH CAROLINA, ASSIGNOR TO PERFECT BOTTLE OPENER COMPANY, OF CHARLOTTE, NORTH CAROLINA, A CORPORATION OF NORTH CAROLINA.

BOTTLE-OPENER.

1,274,140.

Specification of Letters Patent. Patented July 30, 1918.

Application filed November 8, 1917. Serial No. 200,966.

To all whom it may concern:

Be it known that I, ROBERT B. COCHRANE, a citizen of the United States, residing at Charlotte, in the county of Mecklenburg and State of North Carolina, have invented new and useful Improvements in Bottle-Openers, of which the following is a specification.

This invention relates to an improved bottle opener of the broad or general type disclosed in my Letters Patent No. 1,247,507 granted Nov. 20, 1917, such bottle openers being adapted to remove crimped caps from bottles, jars or the like and embodying a plunger for depressing the cap at its center and spreading it along its edge, thereby freeing it from the bottle, and an ejector, whose operation is correlated to that of the plunger, for discharging the cap from the machine.

The invention proposes certain improved features of structure and relation appertaining to the plunger, the ejector and kindred parts; and the principal objects of the invention are to facilitate and lessen the cost of manufacture and to provide a bottle opener which shall be of compact form, shall have great strength and efficient wear resisting properties, whose working parts shall be inclosed and therefore protected and more effectively lubricated, and whose individual parts shall be easily accessible for the purposes of repair or renewal.

An embodiment of the invention is illustrated in the accompanying drawing, wherein:

Figure 1 is a view in side elevation, with certain parts in section, of a bottle opener in which the features of the invention are incorporated, the parts being shown in their normal positions.

Fig. 2 is a vertical longitudinal view of the same but with the various parts in the position which they assume in the operation of the bottle opener.

Fig. 3 is a horizontal sectional view on the line 3—3 of Fig. 2.

Fig. 4 is a detail perspective view of the cap ejector.

Fig. 5 is a detail perspective view of a constructional unit comprising a cap releasing plunger, an ejector controlling plunger and an operating head common to said plungers.

Similar characters of reference designate corresponding parts throughout the several views.

The operating parts are inclosed in a casing 1 which is upright from a supporting base 2 having a bracket 3 at its rear end whereby the machine may be attached to a counter, table or other support.

The cap to be removed from the bottle is acted on by a vertically movable releasing plunger 4 which operates in a guide 5 formed as a part of the casing 1 and at the front thereof.

The machine includes means for supporting the bottle cap to be removed and for alining said cap with the plunger 4 as also for stripping the cap from the bottle when the crimps of the cap have, consequent to the operation of the plunger, been disengaged from the usual bead circumscribing the mouth of the bottle. As shown and preferred such means includes a frusto-conical sleeve 6 formed at the front end of the base 2, an expansible segmental frusto-conical collar 7 inclosed in the sleeve 5, and a supporting ring 8 secured to the lower end of the sleeve 6 and upon which the collar 7 rests. The collar 7 includes a plurality, preferably three, of similar segments 7^a which are normally confined in mutual adjacency to present an uninterrupted circular horizontal section by spring locking means, preferably an annular helical spring 9 which surrounds the segments 7^a with contractile effect. The neck of the bottle is inserted from below through the collar 7 whose segments 7^a yield radially to permit the movement, through and beyond them, of the bottle cap. The edge of the bottle cap rests upon the upper edge or face of the collar 7 which therefore provides a supporting bearing for said cap in opposition to the thrust exerted by the plunger 4.

The bottle cap is discharged from the machine through a clearance 10 with which the casing is formed, said clearance being located between the guide 5 and sleeve 6 and being open to the front and sides of the casing. In order to permit of the discharge of the bottle cap as also of the forward movement of the cap engaging element of the ejector, the upper face of the collar 7 is flush with the upper face of the sleeve 6, the said

sleeve and collar thus providing a platform or ledge across which the cap and the cap engaging element of the ejector may slide.

The cap ejector comprises a cap engaging element or pusher 11 and a bell-crank operating lever 12. The pusher 11 is horizontally disposed and movable and is formed at its front end with a cap engaging yoke 13 of increased width which is always disposed in 5 the clearance 10. The shank of said pusher is disposed between the side walls of the casing 1 and is connected at its rear end by a knuckle joint pivot 14 to the depending arm of the bell crank lever 12, the latter being 10 mounted on a transverse pivot pin 15 which is secured in the side walls of the casing 1.

In order to correlate the operations of the cap releasing plunger 4 and of the ejector, a second plunger 16, preferably located in the 20 rear of the plunger 4, engages the forwardly projecting horizontal arm of the lever 12 and is operated in synchronism with the plunger 4. For this purpose the plungers 4 and 16 are preferably provided with a 25 common operating head 17 from which they are pendent. The ejector is maintained in operative relation to the plunger 16, and for this purpose it is preferred that the depending arm of the bell crank lever 12 shall be 30 backed by a spring 18, preferably a helical spring, which is confined between said arm and the rear wall 19 of the casing 1. For convenience in fitting the ejector in the casing, the rear wall 19 is made removable and 35 is therefore provided at its upper end with a forwardly projecting attachment plate 20 which is secured by a screw 21, said screw being threaded in a transverse web of the casing. In case it should be desired to re- 40 move the ejector from the casing, this can be done very readily, the only operation involved being the removal of the pivot pin 15 (which is threaded in one of the side walls of the casing); and upon the removal of said 45 pivot pin the ejector may be taken out by pulling it forward through the clearance 10. Upon the removal of the ejector the spring 18, if of helical form, may also be removed through said clearance. Said spring may, 50 however, be taken out independently of said ejector by removing the rear wall 19 and pulling said spring rearwardly from between the side walls of the casing.

The plungers 4 and 16 are operated by a 55 cam 22 which engages the head 17 and, together with said head, operates in a clearance provided by ears 23 formed as upward extensions of the side walls of the casing, the cam being mounted on a transverse pivot 60 pin 24 fitted in said ears and being provided with a normally upright operating handle 25.

The various parts are maintained in their normal positions and are reset after each 65 operation of the machine by a spring 26

which, as shown and preferred, is of helical form and surrounds the plunger 4, bearing at its upper end against the head 17 and at its lower end against an abutment 27 formed as an internal shoulder of the guide 5 into 70 which the lower portion of said spring projects. In order to limit the upward movement of the plungers and the return movement of the cam, said cam and the head 17 are formed to provide mutual abutments for 75 one another; and for this purpose the cam is provided with a transverse shoulder 28 which engages the front face of said head.

In case it should be desired to remove the plungers 4 and 16 this can be done very 80 readily, the only operation involved being the removal of the pivot pin 24 (which is threaded in one of the ears 23); and upon the removal of said pivot pin, the cam 22, plungers 4 and 16 and spring 26 may be 85 freely removed by lifting them from between the ears 23.

In the normal relation of the parts, the cap pusher 11 projects across the upper end 90 of the socket 7 but presents no obstacle to the movement of the cap through said socket, owing to the knuckle pivot 14 by which the pusher is connected to the lever 12 and which enables said pusher to yield freely in an upward direction as the cap is pushed 95 upward beyond the socket.

To operate the machine the handle 25 is moved downward and rearward with considerable force whereby to cause the cam 22 to lower the plungers 4 and 16. Said plungers in their downward movement store power in the respective springs 26 and 18; and the plunger 16, acting on the bell crank lever 12, also effects the retraction of the pusher 11 to a position wherein its yoke 13 100 drops behind the cap. Immediately after the retraction of the pusher 11, the plunger 4 engages the cap, depressing its center and thereby causing the spreading of its edge; the crimps of the cap thus being disengaged 110 from the bead at the mouth of the bottle. During the downward movement of the handle 25 the bottle is held in the hand and when the cap is disengaged as described, the gas with which the contents of the bottle 115 may be charged, reacting against the cap will force the bottle downward, thereby completely freeing it from the cap. If the liquid is not carbonated the bottle may be readily pulled downward from the loosened 120 cap.

When the cap is entirely stripped from the bottle the handle 25 is released and thereupon the spring 26 raises the plungers 4 and 16 and, through the agency of the 125 head 17, resets the cam 22 and handle 25. During the upward movement of the plungers the spring 18, acting on the bell crank lever 12, operates the ejector and effects a quick forward movement of the pusher 11 130

whose yoke 18, sharply striking the loose cap, discharges it from the machine.

The present invention although related as species to the invention disclosed in my 5 above mentioned Patent No. 1,247,507, and hence of narrower purview nevertheless admits of certain modifications or variations from the embodiment disclosed which fall within the scope of the appended claims.

10 Having fully described my invention I claim.

1. In a bottle opener, the combination with a plunger operative to release the cap from the bottle and an ejector operative to 15 discharge the released cap of a second plunger controlling the operation of the ejector and an operating means common to both of said plungers.

2. In a bottle opener, the combination 20 with a plunger operative to release the cap from the bottle and an ejector operative to discharge the released cap of a second plunger controlling the operation of the ejector and an operating head common to both of 25 said plungers.

3. In a bottle opener, the combination 30 with a plunger operative to release the cap from the bottle and an ejector operative to discharge the released cap of a second plunger controlling the operation of the ejector, an operating head common to both of said 35 plungers, and a cam acting on said head.

4. In a bottle opener, the combination 40 with a plunger operative to release the cap from the bottle and an ejector operative to discharge the released cap of a second plunger controlling the operation of the ejector, an operating head by which said plungers are carried, and a spring acting to hold both 45 of said plungers and said operating head in a normal position.

5. In a bottle opener, the combination 50 with a plunger operative to release the cap from the bottle of an ejector for the released cap comprising a slidable cap pusher and a bell crank lever to which said pusher is pivoted, and means movable with the plunger when the latter is operated for operating said bell crank lever to withdraw said pusher.

6. In a bottle opener, the combination

with a plunger operative to release the cap from the bottle of an ejector for the released cap comprising a slidable cap pusher and a bell crank lever to one arm of which said 55 pusher is pivoted, and a second plunger movable with the first plunger and co-acting with the other arm of said bell crank lever.

7. In a bottle opener, the combination with a plunger operative to release the cap 60 from the bottle of an ejector for the released cap comprising a slidable cap pusher and a bell crank lever to one arm of which said pusher is pivoted, a second plunger movable with the first plunger and co-acting with 65 said bell crank lever to effect the withdrawal of said cap pusher when the first plunger is operated and a spring acting on said bell crank lever to effect the cap discharging operation of said cap pusher when the first 70 plunger is reset.

8. In a bottle opener, the combination with a plunger operative to release the cap 75 from the bottle of an ejector for the released cap comprising a slidable cap pusher and a bell crank lever to one arm of which said pusher is pivoted, a second plunger co-acting with the other arm of said bell crank lever to control the operation of said ejector and a common operating head for both of 80 said plungers.

9. In a bottle opener, the combination with a plunger operative to release the cap 85 from the bottle of an ejector for the released cap comprising a slidable cap pusher and a bell crank lever to one arm of which said pusher is pivoted, a second plunger co-acting with the other arm of said bell crank lever to control the operation of said ejector, a common operating head for both of 90 said plungers, a spring for resetting both plungers and their operating head and a second spring for actuating said ejector as the plungers are reset.

In testimony whereof I have hereunto set 95 my hand in presence of two subscribing witnesses.

ROBERT B. COCHRANE.
